UNITED STATES PATENT OFFICE.

NAPOLEON DU BRUL, OF CINCINNATI, OHIO.

DESIGN FOR A FRAME FOR CIGAR-BUNCHING MACHINES

SPECIFICATION forming part of Design No. 23,702, dated October 16, 1894.

Application filed April 9, 1894. Serial No. 506,949. Term of patent 14 years.

To all whom it may concern:

Be it known that I, NAPOLEON DU BRUL, a citizen of the United States, residing at Cincinnati, in the county of Hamilton and State 5 of Ohio, have invented and produced a new and original Design for a Frame for Cigar-Bunching Machines, of which the following is a specification, reference being had to the accompanying drawing, showing a perspective 10 view thereof.

The leading feature of my design consists in a convex plate crossing the upper end of the vertical transverse plate and provided with an inclined wall, a horizontal portion in 15 front of the wall and an inclined shelf, and a trough shaped portion between the horizontal portion and the inclined shelf.

1 represents a vertical transverse plate having a cylindrical portion at its lower end and 20 a cylindrical portion on the inner side near

its lower end. Crossing the upper portion of the vertical plate is a horizontal plate 3 having a surmounting shoulder 3^a at its inner side.

2 is a convex plate crossing the upper end of the vertical plate and provided with an 25 inclined wall and horizontal portion 2^a in front of the wall, a trough shaped portion 2^b in front of the horizontal portion and an inclined shelf 2^c in front of the trough shaped portion.

Having thus described my invention, the 30 following is what I claim as new therein and desire to secure by Design Letters Patent:

The design for a frame for cigar bunching machines, substantially as herein shown and 35 described.

NAPOLEON DU BRUL.
